APPARATUS FOR EXTRUDING METAL SHEATH OR PIPE

George Allen Seeley, Baltimore, Md., assignor to
Western Electric Company, Incorporated, New
York, N. Y., a corporation of New York

Application November 20, 1937, Serial No. 175,611

2 Claims. (Cl. 207—17)

This invention relates to apparatus for extruding metal sheath or pipe, and more particularly to apparatus for extruding lead sheath for cables.

5 An object of the invention is to provide apparatus for facilitating the control of the concentricity and uniformity of extruded metal pipe or sheathing.

In accordance with one embodiment of the invention, the lead is first extruded through a tapering annular orifice of decreasing cross section, then through an annular orifice parallel to the axis of the core being covered, but spaced therefrom from where the metal passes into a 10 conical aperture, reducing the diameter of the sheath, and thence through a sizing opening. The behavior of the metal during these steps is controlled by a control of the temperature of the metal.

20 A complete understanding of the invention may be had by reference to the following description, taken in conjunction with the accompanying drawing, in which

Fig. 1 is a cross-sectional view of an extrusion head embodying the invention;

Fig. 2 is an enlarged cross-sectional view of the die showing a portion of the core tube; and

Fig. 3 is a fragmentary end view of the die looking in the direction of the arrows 3—3 in Fig. 2.

Referring now more in detail to the drawing, a die block 6 is shown which receives heated plastic lead from an extrusion cylinder not shown. Mounted in the die block is an inner die member 35 or core tube 7 co-operating with a die 8 to form the lead around a core of insulated conductors or the like. The die is held in place by means of a threaded outlet member 11.

When pressure is exerted on the plastic lead 40 in the extrusion chamber, it is forced into a tapering annular orifice 12 whose cross-section diminishes toward the outlet end of the die. This chamber produces a gradual reduction in the sheath being formed and aids in holding the 45 core tube 7 concentrically in the die. From the opening 12 the sheath being formed passes into an annular space 13, the walls of which are parallel to the axis of the sheath and core, although the sheath at this point is spaced a distance from 50 the core. In this space the weight and concentricity of the sheath are determined. From the 55 annular space of passage 13 the sheath passes into a portion 14 of the die opening in which the walls taper inwardly toward the outlet end of the die to uniformly reduce the diameter of the

sheath. The temperature of the metal being extruded is so controlled that the space between the wall 14 and the core does not fill up; in other words, the metal is sufficiently rigid at this point so that its only increase in thickness is due to the reduction in the diameter of the sheath. From this portion of the die opening the sheath passes through a sizing opening whose walls are parallel to the axis of the sheath and core.

The temperature of the metal in the die during the extrusion process is controlled by passing steam or other suitable cooling medium through the die. A steam supply pipe 16 is connected to a passage 17 in the die holding member 11 and connects to a passage 18 in the die. 15 From the passage 18 the cooling medium enters an annular passage 19 circulating around the die to a connecting passage 21 which connects with a second annular passage 22. From the passage 22 the cooling medium enters a connecting passage 23 and passes into a third annular passage 24. From the passage 24 the cooling medium is conducted to a final annular passage 25 from which the steam escapes around the exterior of the sheathed cable through the die holding member 11 which has a larger internal diameter than the external diameter of the sheathed cable. This cooling system insures the proper cooling of the metal in the extrusion die and in conjunction with the die produces a 20 cable of uniform concentricity and weight.

It will be understood that the nature and embodiment of the invention herein described is merely illustrative and that many changes and 25 modifications may be made therein without departing from the spirit and scope of the invention.

What is claimed is:

1. In a metal sheath extruding apparatus, an 10 extruding head for receiving plastic metal under pressure, a die member having an internal diameter greater than the external diameter of a core to be sheathed, a core tube co-operating with said die member to form a tapering annular 15 orifice, a second tapering annular orifice of smaller diameter, both diminishing toward the outlet end of said die member, a third annular orifice between said first-named orifices the walls of which are parallel to and spaced away from 20 the axis of a sheath to be formed, a fourth and final sizing orifice for uniformly controlling the diameter of said sheath, and means for controlling the temperature of said sheath by the circulation of a cooling medium comprising a plu- 25

rality of annular passages in the said die member.

2. In a metal sheath extruding apparatus, an extruding head for receiving plastic metal from a source, a die member having an internal diameter greater than the external diameter of a cable to be sheathed, a core tube co-operating with said die member to form a tapering annular orifice diminishing toward the outlet end of said die member, a second annular orifice the walls of which are parallel to and spaced away from the axis of a sheath to be formed, a third orifice diminishing toward

the outlet end of said die member, said last orifice uniformly reducing the diameter of said sheath, and means for controlling the temperature of said sheath by the circulation of a cooling medium comprising a plurality of annular passages in said die member, the first of said annular passages being farthest from and each succeeding passage approaching nearer the axis of the extruded sheath, the final passage being nearest to and discharging around the exterior of 10 the completed extruded sheath. 5

GEORGE ALLEN SEELEY.
